**DRYER FOR PHOTOGRAPHIC TYPE EMULSION
COATED SHEETS**

Henry N. Fairbanks and Daniel H. Robbins, Rochester, N.Y., assignors, by mesne assignments, to Itek Corporation, Lexington, Mass., a corporation of Delaware

Filed Oct. 4, 1963, Ser. No. 313,880
7 Claims. (Cl. 34—123)

The present invention relates to an improved apparatus for drying emulsion coated carrier sheets. More particularly the invention is related to a dryer for photographic type emulsion coated sheets. In particular, the invention is directed to a dryer for automatic offset plate processors for offset plates having one side coated with plastic and an opposite side coated with image receiving emulsion.

Offset plate processors are available for automatically processing projection offset plates such as the type marketed by the assignee under the trademark "Project-A-Lith." This material is a silver halide emulsion on a support, which upon development results in an image area which is oleophilic and a non-image area which is hydrophilic. The automatic processor of the type disclosed in the copending application has as one of its features, the ability to produce offset plates at a rapid rate. The device disclosed therein is capable of producing offset plates on a continuous basis at the rate of approximately two per minute. In order to maintain a two per minute overall continuous production rate, it is desirable that a compatible dryer operate at the same rate. Coupled with the problem of relatively short drying time is the relatively low maximum temperature at which the offset plate becomes adversely affected. The offset plate is a plastic coated carrier sheet having an emulsion coating on one of the plastic coated sides. Both the plastic and emulsion have relatively low softening temperatures, e.g. in the order of 185° F. If either material is heated above these temperatures it would tackify and stick to the transport and dryer. In addition when the emulsion temperature rises above a critical level, e.g. 170°—190° F., it discolors, whereby the plate quality is deteriorated. In addition to quality being affected by excessive temperature, it has also been observed to be affected by the uniformity with which drying occurs. Some of the other problems associated with the drying of this type of material arise due to the softness of the emulsion as it emerges from the processor. Therefore, transporting the plate through the dryer must be accomplished without marring or embossing the emulsion surface, whereby the plate quality will be deteriorated. Dryers known in the art do not produce the uniform, rapid drying, at controlled low temperatures, without physical damage to the emulsion that is required in the drying of a material such as "Project-A-Lith."

Some prior art devices use heated air for drying photographic type emulsions. One such device is shown in U.S. Patent No. 2,869,246 issued January 20, 1949 to Walter Buschmann and Walter Buhren. Devices of this general type require large volumes of air available at the emulsion surface in order to keep the emulsion temperature relatively low and at the same time drying rapidly to match the output of an automatic processor of the type disclosed in the assignee's copending application. Other dryers for photographic type emulsions, transport the sheet on a web over a heated drum. The web absorbs any chemical left on the surface of the plate after processing. The gradual build-up of these chemicals in the web adversely affects both dryer operation and plate quality (i.e., staining of the emulsion). In addition the fibrous threads, characteristic of the absorbing web, tend to be picked up by the relatively soft emulsion during the drying process. Foreign material attached to the plate

2

would adversely affect the quality of prints produced from the plates. It is also known in the art, to use heated platen devices for drying. However, it has been observed that drying efficiency in these devices is affected by uniformity of contact between the material to be dried and the platen. If an air space develops between the material and the platen, drying in the area of the air space is inhibited resulting in non-uniform plates. Thus, prior art dryers do not produce practical, uniform, rapid drying at controlled low temperatures without physical damage to a relatively soft emulsion coated offset plate material.

It is an object of this invention, therefore, to provide an improved apparatus for drying photographic type emulsion coated sheets which avoids one or more disadvantages of the prior art.

It is a further object of this invention to provide an improved apparatus for drying photographic type emulsion coated sheets at a rapid rate and at relatively low temperatures.

It is a further object of the invention to provide an improved dryer for photographic type emulsion coated sheets that produces uniform drying across the face of the emulsion.

It is still a further object of the invention to provide an improved apparatus for drying photographic type emulsion coated sheets wherein the emulsion surface is unmarred during transportation through the dryer.

In accordance with the present invention there is provided an improved apparatus for drying photographic type emulsion coated sheets. The apparatus comprises a housing having an inlet opening and a discharge opening. A heated platen is disposed within the housing. A portion of the platen surface defines a path along which the sheets travel through the dryer. There is provided contact means for holding the sheets in intimate contact with the path defining portion of the platen. The contact means holds the sheets in contact with the platen as the sheets travel along the defined path for causing heat conduction through the sheet to the emulsion coating. The contact means are spaced to permit vaporization of moisture from the emulsion. There are also provided means disposed along the path to accelerate vaporization of moisture from the emulsion coating after the moisture has been initially heated by the platen. Transport means are provided for transporting the sheet in the defined path from the inlet along the platen, to the discharge opening whereby the emulsion coated sheets are dried.

For a better understanding of the present invention together with other and further objects thereof, reference is made to the following description taken in connection with the accompanying drawings and its scope will be pointed out in the appended claims.

FIG. 1 is a schematic illustration of the principles of operation of a dryer embodying the present invention;

FIG. 2 is a perspective view, partially cut away of a dryer embodying the present invention;

FIG. 3 is a sectional view taken along line 3—3 in FIG. 2; and

FIG. 4 is an end view, partially in section, of another embodiment of the present invention.

Referring now in more detail to the drawings and with particular reference to FIG. 1 there is here schematically illustrated the broad principles of operation of the invention. The dryer broadly operates by first conducting heat to the moisture to be removed and then accelerating vaporization by forcing air against the preheated moisture. A typical material to be dried is designated by the numeral 10. This material, by way of example only, has four layers. An emulsion layer 10a, a plastic coating

10b, a carrier sheet **10c**, and a plastic coating **10d**. The sheet **10** is fed into the dryer housing **11** so that the plastic coating **10d** is in contact with a heated platen **12**. The platen is heated from a heat source **13** which may, for example, be a source of radiant energy. A control **16** controls the electrical input (i.e., voltage), to the heat source. The platen source is maintained at a substantially constant temperature through a feedback loop consisting of a sensor **14** and control **16**. The sensor measures the platen temperature while the control is set for a desired reference temperature. The difference between the two temperatures causes the control **16** to energize or deenergize the heat source **13**. A contact means **18** maintains the sheet in intimate contact with the platen during a portion of its travel in the dryer, thereby preventing air spaces from developing between the platen and the sheet. Any air space would be a local insulator causing non-uniform drying of this sheet. As a practical matter, it has been found that most of the moisture in this type of material, as it enters the dryer, is in the emulsion. The material is squeegeed prior to drying, removing most of the moisture from the plastic coated exposed surface. The contact means **18** is provided with perforations **21** for allowing the moisture to escape from the emulsion layer **10a**. The emulsion layer is heated by conduction of heat from the platen **12** through the layers **10d**, **10c**, and **10b**. The temperature of the emulsion surface rises initiating vaporization of the moisture at the surface. By way of example, the critical temperature beyond which "Project-A-Lith" emulsion can be heated is in the order of 170°-190° F. A blower **19** is mounted in the housing **11** and blows ambient air in the direction **A** against the emulsion surface to accelerate vaporization of moisture therein. An exhaust system, shown by the exhaust fan **20**, may be added to further accelerate vaporization. The exhaust fan continuously removes moisture from the housing **11** in the direction **B** preventing the humidity level from rising therein.

Referring now in more detail to FIG. 2, there is here shown a perspective view, partially cut away, of the preferred embodiment of a dryer embodying the present invention. The dryer is contained in a housing generally designated by the numeral **30**. The housing has an inlet opening **31** in its forward vertical wall and discharge opening **32** in its rear vertical wall. The openings are generally rectangular in shape for receiving photographic sheet material. Adjacent the inlet opening **31** is a curved guide **33** for deflecting and guiding the leading edge of the sheet to be dried towards a rotatable cylindrical platen **34**. The platen **34** has a cylindrical section **34a** and a pair of circular end plates **34b** only one of which is shown in FIG. 2. The end plates are fastened to the cylindrical section **34a** by means of screws **35**. The end plates have bearings **36** mounted therein. One bearing is shown in FIG. 2. Associated with each bearing **36** is a snap ring **60** for preventing axial shifting of the platen assembly along shaft **37**. The platen assembly is rotatable about stationary shaft **37**, which is secured to the housing **30**. The assembly is rotated by means of a motor **38** mounted on top of housing **30** in a motor housing **39**. A chain drive connects the motor **38** to a sprocket **39** mounted on the end of shaft **40**. The opposite end of shaft **40** has a pulley **41** thereon around which is wrapped a garter spring **42**. The garter spring **42** connects the pulley **41** to the cylinder **34a**. The garter spring **42** is under tension therefore rotating platen **34** as pulley **41** is rotated. Also mounted on shaft **40** is a plurality of spaced rollers **43**. As seen more clearly in FIG. 3 which is a vertical section taken along line **3-3** in FIG. 2, the rollers **43** have endless belts **44** coupled thereto. The endless belts pass over rollers **45**, **46**, and **47** mounted on shafts **48**, **49**, and **50** respectively. As the pulley **43** is rotated the portion of belt **44** in contact with the platen **34** travels in the same direction as the platen, thus transporting the paper in contact with the

platen to allow heating of the sheet by the platen. Since the emulsion surface is soft, it is desirable that the belts **44** do not exert any excessive pressure on the sheet during transport. Therefore, means are provided for adjusting the tension in belts **44** by means of slots **63** disposed in opposite vertical walls of housing **30** (see FIG. 3 wherein one slot is shown). Shaft **49** is provided with the threaded ends **64** which protrude through slots **63** allowing the tension to be adjusted by vertical alignment of shaft **49**. Nuts are used to clamp the shaft in place after alignment. For the sake of clarity, the means for rotatably mounting the shafts on the housing and the means for fixedly mounting the shaft **37** to the housing have not been shown. Any of the means well known in the art for accomplishing the desired result may be used. For example, the rotatable shafts may be mounted in sleeve bearings which are held in trunions on the housing, the trunions for shaft **49** being adjustable vertically as the shaft is adjusted. The stationary shaft **37** may be bolted to the housing. The platen is heated by a heat source **51** which may for example be an infrared lamp, which is coupled to shaft **37** by two brackets on either end of the shaft, one of which is shown at **52**. The belts **44** are preferably porous to allow moisture to pass therethrough, and spaced to leave a maximum area on the sheet material exposed to the housing environment for the purpose of vaporizing moisture from the surface thereof. To accelerate vaporization, a blower **53** is mounted in the housing **30**. The blower **53** forces ambient air against the exposed surface of the sheet thus accelerating vaporization of moisture on the exposed surface which has been initially heated by conduction from platen **34**. An exhaust fan **54** may be provided for removing accumulated moisture from the housing **30** thus controlling the humidity level therein. The exhaust fan **54** is also mounted in the housing **30**. A temperature sensor **60**, which may be a thermocouple or thermistor is coupled to the platen for providing an indication of the platen temperature. This cooperates with a control device as was explained with reference to FIG. 1. Shaft **40** is provided with a plurality of pulleys **43** supporting endless belts **55** disposed between the belts **44** for transporting paper from the platen towards the exit opening **32**. The endless belts **55** are disposed about pulleys **56** on shaft **40** and pulleys **57** on shaft **58**. An exit guide **59** is provided for guiding sheet towards the exit opening **32**. A spring **61** is coupled to guide **59** and resiliently bears against belt **55**. When the sheet passes between spring **61** and belt **55** it is driven by belts **55** through the exit opening **32**. The operation of the dryer will be explained with reference to FIGS. 2 and 3. Prior to use, the platen **34** is preheated by energizing the heat source **51**. The motor **38** is energized causing the chain drive to drive sprocket **39** in the direction of arrow **C** shown on shaft **40**. The sprocket **39** in turn drives shaft **40** in the same direction causing belts **44** to move in the direction of arrow **E** and the platen **34** to rotate in the direction of arrow **E**. The belts **55** move in the direction of arrow **F**. The photographic emulsion is fed into the dryer through the inlet opening **31** with its emulsion side down. The leading edge of the sheet contacts guide **33** and is directed towards the platen **34**. The leading edge, thereafter, engages the portion of belts **44** in contact with the platen on the side nearest the inlet opening **31**. The sheet is then transported in contact with the rotating platen toward the exit side of the dryer. During transport along the platen, the emulsion surface is away from the platen whereby moisture in the emulsion is heated by heat conduction through the platen to the emulsion surface. As the sheet reaches the vicinity of blower **53** ambient air is forced against the emulsion surface by the blower accelerating vaporization of the moisture that has been preheated by conduction from the platen. In order to achieve maximum vaporization of the moisture from the

sheet, belts 44 are porous and spaced. The sheet continues to travel in the dryer until the leading edge engages the guide 59 at which point the sheet is directed toward the exit opening 32. The leading edge travels along the guide 59 until it passes between spring 61 and belt 55. The sheet is then driven through the exit opening by the combination of belt 55 and spring 61. The sheet emerges from the dryer with its emulsion side down. An exhaust fan 59 removes air from the housing. The removal of air from the housing lowers the humidity level as well as lowering the housing temperature. Lowering the housing temperature causes a greater temperature drop across the platen and sheet increasing the amount of heat flow therethrough at a given input temperature.

Another embodiment of the invention in FIGS. 2 and 3 is illustrated in FIG. 4. In this embodiment a receiving bin 62 is mounted on the rear wall of the housing 30. As the sheet 10 emerges from the dryer through the exit opening 32, with its emulsion side down, it slides down the rear wall of bin 62. As the sheet lies in the bin, the emulsion side would be facing the discharge of the exhaust blower 54. Although this air from the exhaust blower is slightly damp, it is heated and it has been found to be useful in further drying the sheets.

While we have described what is presently considered a preferred embodiment of our invention, it will be obvious to those skilled in the art that various changes and modifications may be made therein without departing from the inventive concept, and it is aimed in the appended claims to cover all such changes and modifications as fall within the true spirit and scope of our invention.

What is claimed is:

1. In a dryer for drying sheet material:
  - (a) a curved platen having a sheet contact surface associated therewith;
  - (b) a plurality of spaced flat sheet transport belts;
  - (c) means for causing said flat belts to contact the sheet contact surface associated with said curved platen, the ratio of the sum of the widths of said flat belts over the width of said sheet contact surface

of said platen being such as to leave wide spaces between said belts for the purpose of vaporizing moisture therefrom;

- 5 (d) means for driving said belts to cause said sheet material to be transported through said dryer between said curved platen and said belts, and
- (e) means for causing drying gas to pass over at least a portion of said sheet contact surface of said curved platen to accelerate the drying of said sheet material.
- 10 2. The combination as set forth in claim 1 wherein said belts are made of non moisture absorbent material having apertures formed therethrough for allowing vapor to escape from said sheets through said apertures.
- 15 3. The combination as set forth in claim 1 further including a sheet receptacle means for receiving sheet material emerging from said dryer and means for directing said drying gas from the interior of said dryer to said receptacle to further dry said sheet material present thereon.
- 20 4. The combination as set forth in claim 1 wherein means are provided for heating said curved platen.
5. The combination as set forth in claim 2 wherein means are provided for heating said platen.
- 25 6. The combination as set forth in claim 1 wherein said means for driving said belts also drives said platen at the same tangential velocity as the velocity of said belts.
7. The combination as set forth in claim 2 wherein said means for driving said belts also drives said platen at the same tangential velocity as the velocity of said belts.
